UNITED STATES PATENT OFFICE.

EDSON O. SESSIONS, OF CHICAGO, ILLINOIS.

LOCKING-SWITCH.

1,366,503.

Specification of Letter's Patent. Patented Jan. 25, 1921.

Application filed November 2, 1917. Serial No. 199,971.

To all whom it may concern:

Be it known that I, EDSON O. SESSIONS, a citizen of the United States, residing at Chicago, in the county of Cook and State of Illinois, have invented a certain new and useful Improvement in Locking-Switches, of which the following is a specification.

My invention relates particularly to an improved construction of locking switch of 10 the lock-in lock-out type as used for example in connection with oil switches for controlling the connection of the main feeders to the mechanism of the oil switches, so that the oil switches may be disconnected from 15 the main feeders when it is desirable to repair or inspect the oil switches. In connection with switches of this kind it has become necessary with the development of high tension alternating current systems to provide 20 locking devices of the strongest and most positive kind so that the switches may be held in their closed position securely to guard against the heavy lateral thrusts exerted on the switch blades by an undue rush 25 of current as for example when a total or partial short circuit occurs on the devices supplied with current from the oil switches and furthermore the switches must be positively locked in open position when the oil 30 switches are disconnected from the main feeders so that the danger of the switches accidentally becoming closed while the oil switches are being inspected or repaired is eliminated. To secure the results now 35 found to be necessary in practice I find it desirable to provide locking mechanism carried by the switch blades which coöperates with devices adjacent the clip contact of the switch as distinguished from the pivot clip, 40 so that the locking of the switch in its closed position may be accomplished in the most effective manner, and I also provide devices associated with the support of the pivot contact for engaging the locking mechanism to 45 hold the switch blades in their open position.

It will be understood that oil switches are usually mounted in inclosed casings with cut-out switch compartments below the oil 50 switch compartments, the dimensions of the cut-out switch compartments in practice being no larger than is required to give a safe distance through the air between the terminals connected with the main feeders 55 and the terminals connected with the oil

switch to prevent passage through the air of current, as a result of the voltages employed. My present invention has for its purpose the production of a locking switch, which while it secures the desired results 60 already referred to, also maintains the highest possible striking distance between the terminals in the cut-out switch compartment, thus maintaining to the highest degree the striking distance between the terminals in the cut-out switch compartment. 65

My invention will best be understood by reference to the accompanying drawings showing preferred embodiments of my invention, in which—

Figure 1 shows in side elevation the portion of a cut-out switch compartment with my locking switch in place,

Fig. 2 shows a detail view on an enlarged scale of the locking mechanism, a part of 75 the casing being broken away to more clearly show said mechanism,

Fig. 3 is a view showing in front elevation the parts shown in Fig. 2,

Fig. 4 is a view similar to Fig. 1 showing a modified construction of switch, and

Fig. 5 is a view similar to Fig. 2 showing a modified construction of locking mechanism.

Fig. 6 shows in a view similar to Fig. 5 a 85 further modified construction of the locking mechanism.

Similar numerals refer to similar parts throughout the several views.

As shown in Fig. 1 the walls of the cut-out switch compartment are indicated in dotted lines at 10 and in the bottom wall an insulator 11 is mounted to support the terminal of the corresponding main feeder while in the top wall of the compartment a 95 second insulator 12 is mounted to support the lower terminal of the corresponding oil switch mechanism. A conducting stud 13 projects below the insulator 12 and has rigidly secured to it a first support 14 while 100 the insulator 11 has projecting from it a conducting stud 15 to which is rigidly secured a second support 16, these supports serving to support the cut-out switching mechanism.

The support 14 is in the form of a laterally extending bracket and has rigidly secured thereto the pivot clip 17 of the switch and to this pivot clip the switch blade or blades 18 are pivotally secured at 19. The 110

other end of the switch blade or blades engage, when they are in their closed position, the contact clip 20 rigidly supported by the support or bracket 16. The free end of the 5 switch blades carry a casing 21 from which a first locking latch 22 extends to engage a catch 23 adjacent the clip contact 20 and a second locking latch 24 projects from said casing to engage a catch 25 carried by the 10 support 14.

To maintain as great a striking distance as possible between the conducting parts carried by the studs 13 and 15 when the cut-out 15 switch is in its open position, the casing 21, as more clearly shown in Fig. 3, is preferably mounted between two adjacent switch blades 18 being secured thereto by a block or bracket 26 by means of suitable rivets or bolts 27 extending through the block and switch 20 blades.

The construction of the locking mechanism contained in the casing 21 is best shown in Fig. 2, and as seen in that figure the latch 22 is pivotally mounted on a rod 28 carried by 25 the casing and at its other end is provided with a slot for receiving a pin 29 carried by an operating member 30 which is pivotally supported upon a rod 31 carried by the casing 21. The member 30 extends beyond its pivot 30 rod 31 and overlaps slots 32 formed through the opposite walls of the casing 21 to receive a suitable operating tool not shown. A second operating member 33 is pivotally supported in the casing upon a rod 34 carried 35 by the casing and this operating member is in the form of a bell crank lever the short end of which is provided with a slot for engaging a pin 35 carried by the member 30. The longer end of the bell crank lever extends 40 over the slots 32. A helical spring 36 is mounted between the operating members 30 and 33 and secured at its ends to pins carried by the said operating members as a result of which said operating members are normally 45 held together against an abutment 37 extending into the casing 21. As a result of the construction described when the operating tool is inserted through the slots 32 between the operating members 30 and 33 a pull toward 50 the right on the tool exerts a corresponding pressure on the lower end of the operating member 30 which rotates said operating member around to the left on its pivot rod 31 and the pin 29 rotates the latch 22 around 55 to the right on its pivot rod 28 thus releasing the latch from engagement with the catch 23. On the other hand if the operating tool is moved to the left for the position of the parts shown in Fig. 2 a corresponding pressure is exerted on the operating member 33, 60 which rotates the operating member 33 around to the right on its pivot rod 34 as a result of which the engagement between the operating member and the pin 35 rotates the 65 operating member 30 around to the left on

its pivot rod 31, which in the manner described moves the latch 22 to its releasing position.

The latch 24 is pivotally supported in the casing 21 on a rod 38 carried by the casing 70 and is provided with an extending portion having a slot engaging a pin 39 carried by the operating member 30, the relation of the parts being such that rotation of the operating member 30 around to the left on its pivot 75 rod rotates the latch 24 around to the right on its pivot rod, thus moving the latch 24 to its releasing position.

It will be noted that the slots 32 extending through the casing 21 are curved toward 80 the pivot 19 of the switch blades adjacent the operating member 33. The purpose of this will best be understood by reference to Fig. 1. As shown in that figure it will be observed that the insulator 12 is at some distance from the front right hand side of the casing containing the switching mechanism, which is necessary in oil switch construction, as a result of which the lower right hand corner of the compartment containing the oil 90 switch mechanism is in a position making it impossible to place the operating tool in a vertical position when it is inserted in the slots 32 to move the switch from its open position to its closed position. In practice 95 it is seldom possible to arrange the parts of the cut-out switch so that the operating tool can assume a position more nearly vertical than 45 degrees with a horizontal plane and with the slots 32 extending vertically, a longitudinal thrust exerted on the operating tool in the position referred to could not be communicated effectively to the operating member 33 to release the latch 24 from the catch 25. By giving the slots 32 a curved formation as described and correspondingly shaping the end of the operating member 33 the thrust exerted on the operating tool is effectively communicated to the operating member 33 and the locking mechanism is 100 easily operated to release the latch 24 from the corresponding catch. It will also be observed that if the slots 32 were given a 45 degree inclination to the axis of the switch blades throughout the entire length of said 105 slots, when the operating tool is inserted through the slots to open the switch from its closed position the thrust exerted upon the operating tool would with difficulty operate the operating mechanism on account of the 110 inclination of the operating tool to the slots, as a result of which the portions of the slots adjacent the operating member 30 are preferably formed to extend at substantially right angles to the longitudinal axis of the switch 115 blades.

From the above description it will appear that by mounting the locking mechanism in a casing separate from the switch blades the locking mechanism may be made as rigid 130

and strong as may be necessary to meet any practical requirements and furthermore since the locking mechanism with the exception of the projecting latches 22 and 24 is entirely 5 inclosed within the casing 21, the parts are effectively protected from dirt and foreign matter getting into the locking mechanism and the mechanism is further protected from injury due to improper handling of the operating tool or tampering.

In Fig. 4 a construction is illustrated which may be used where the distance between the terminals is somewhat greater than that assumed in Fig. 1 or the voltages 15 employed are sufficiently less than those used in Fig. 1, so that the casing of the locking mechanism may be mounted on the ends of the switch blades. In this construction the support or bracket 14^a is similar to the 20 bracket 14 shown in Fig. 1 and similarly supports the switch blades 18^a. The second support 16^a in this construction extends upwardly and to the left at an angle to support the contact clip 20^a at a sufficient distance 25 from the lower terminal stud 15^a, so that the entire casing 21^a for the locking mechanism is located below and to the right of the contact clip 20^a, the casing being connected to the extreme ends of the switch 30 blades 18^a. The locking mechanism may be the same as described above in connection with Figs. 1 and 2.

In the modified form of locking mechanism shown in Fig. 5 the switch blades 18^b 35 carry at or near their free ends a casing 21^b in which there is pivotally supported a double latch 40 on a rod 41 carried by the casing. The portion 40^a of the latch is similar to the latch 22 above described and serves 40 the same purpose while the portion 40^b is similar to the latch 24 described above and performs the same purpose as the latch 24. The double latch 40 is provided with an offset portion having a slot engaging a pin 42 45 carried by a first operating member 43 which is pivotally mounted on a rod 44 carried by the casing 21^b. The operating member 43 is extended beyond its pivot rod to overlap the slots 32^a formed through the opposite 50 walls of the casing 21^b to receive an operating tool and a second operating member 45 is pivotally mounted in the casing 21^b on a rod 46 carried by the casing and this operating member is provided with an extending 55 portion having a slot engaging a pin 47 carried by the operating member 43. The operating member 45 overlaps the slots 32^a at their ends opposite the operating member 43. A helical spring 48 is connected at 60 its ends to the operating members 43 and 45 to normally hold them against an abutment projecting into the casing 21^b. The slots 32^a and the relation of the operating members 43 and 45 thereto are similar to the slots 32 65 and the relation of the operating members

30 and 33 thereto and the locking mechanism shown in Fig. 5 is operated in the same manner as that described above for the locking mechanism shown in Fig. 2. The locking mechanism shown in Fig. 5 has the advantage of fewer parts than that shown in Fig. 2 and may be employed where there is opportunity to place the catches so that they may be engaged by the double latch.

While I have shown my invention in the particular embodiment above described it will be understood that I do no limit myself to these exact constructions as I may employ equivalents thereof known to the art at the time of the filing of this application without departing from the scope of the appended claims.

The modified construction shown in Fig. 6 is similar to that shown in Fig. 5 as to the general construction and disposition of the locking latch of the operating members. In this construction the casing 21^c carried by the switch blade 18^c pivotally supports within said casing a double locking latch 49 having a projecting lug 49^a engaging a corresponding notch formed in the end of the operating member 50, which operating member is pivotally supported in the casing and operates in a manner similar to the operating member 43 shown in Fig. 5. A second operating member 51 similar to the operating member 45 in Fig. 5 and similarly supported in the casing 21^c is provided with a lug 51^a engaging a corresponding notch in the side of the operating member 50, as a result of which the operation of either operating member by an operating tool operates the double latch 49 to move it to its releasing position in substantially the manner described in connection with Fig. 5. In the construction shown in Fig. 6 a helical spring 52 is disposed with one end in engagement with a pin carried by the latch 49 and the other end secured to the casing 21^c in a manner to hold the latch 49 in its locking position.

What I claim is:

1. A locking switch of the lock-in lock-out type, the combination of a first support, a pivot clip carried by said support, a switch blade pivoted to said pivot clip, locking mechanism carried by said switch blade, a second support, a contact clip carried by said second support for engaging said switch blade in its closed position, a catch carried by said second support engaging said locking mechanism in the closed position of said switch, and a catch carried by said first support engaging said locking mechanism in the open position of said switch.

2. In a locking switch of the lock-in lock-out type, the combination of a first support, a pivot clip carried by said support, a switch blade pivoted to said pivot clip, locking mechanism carried by said switch blade, a

second support, a contact clip carried by said second support for engaging said switch blade in its closed position, a catch carried by said second support engaging 5 said locking mechanism in the closed position of said switch, and a catch carried by said first support engaging said locking mechanism in the open position of said switch, and a casing carried by said switch 10 blade for containing said locking mechanism, said casing having slots through its opposite walls for receiving an operating tool, said slots having one inclination to said switch blade at one end and a different inclination to said switch blade at the other end of said slots.

3. In a locking switch of the lock-in lock-out type, the combination of a first support, a pivot clip carried by said support, a switch 20 blade pivoted to said pivot clip, locking mechanism carried by said switch blade, a second support, a contact clip carried by said second support for engaging said switch blade in its closed position, a catch carried 25 by said second support engaging said locking mechanism in the closed position of said switch, and a catch carried by said first support engaging said locking mechanism in the open position of said switch, and a casing 30 carried by said switch blade for containing said locking mechanism, said casing having slots through its opposite walls for receiving an operating tool, said slots having one inclination to said switch blade at one end 35 and a different inclination to said switch blade at the other end of said slots, said locking mechanism comprising latching mechanism for engaging said catches, and two operating members articulating with 40 said latching mechanism, one of said operating members overlapping said slots at one end thereof and the other of said operating members overlapping said slots at the other end thereof, whereby motion of either operating member away from the middle portion of said slots releases said latching mechanism.

4. In a locking switch of the lock-in lock-out type, the combination of a first support, 50 a pivot clip carried by said support, a switch blade pivoted to said pivot clip, locking mechanism carried by said switch blade, a second support, a contact clip carried by said second support for engaging said switch blade in its closed position, a catch carried by said second support engaging said locking mechanism in the closed position of said switch, and a catch carried by 55 said first support engaging said locking mechanism in the open position of said switch, and a casing carried by said switch blade for containing said locking mechanism, said casing having slots through its opposite walls for receiving an operating tool, said slots having one inclination to said switch blade at one end 60 and a different inclination to said switch blade at the other end of said slots, said locking mechanism comprising latching mechanism for engaging said catches, and two operating members articulating with 65 said latching mechanism, one of said oper-

switch blade at one end and a different inclination to said switch blade at the other end of said slots, said locking mechanism comprising latching mechanism for engaging said catches, and two operating members 70 articulating with said latching mechanism, one of said operating members overlapping said slots at one end thereof and the other of said operating members overlapping said slots at the other end thereof, whereby motion of either operating member away from the middle position of said slots releases said latching mechanism, a spring secured to said operating members and tending to hold them together, and an abutment carried 75 by said casing for holding said operating members a sufficient distance apart to permit the insertion of an operating tool.

5. In a locking switch of the lock-in lock-out type, the combination of a first support, 80 a pivot clip carried by said support, a switch blade pivoted to said pivot clip, locking mechanism carried by said switch blade, a second support, a contact clip carried by said second support for engaging 85 said switch blade in its closed position, a catch carried by said second support engaging said locking mechanism in the closed position of said switch, and a catch carried by said first support engaging said locking 90 mechanism in the open position of said switch, and a casing carried by said switch blade for containing said locking mechanism, said casing having slots through its opposite walls for receiving an operating 95 tool, said slots having one inclination to said switch blade at one end and a different inclination to said switch blade at the other end of said slots, and a bracket carried by 100 said switch blade between its pivot clip and its contact clip for supporting said casing.

6. In a locking switch of the lock-in lock-out type, the combination of a first support, a pivot clip carried by said support, a switch blade pivoted to said pivot clip, locking 110 mechanism carried by said switch blade, a second support, a contact clip carried by said second support for engaging said switch blade in its closed position, a catch carried by 115 said second support engaging said locking mechanism in the closed position of said switch, and a catch carried by said first support engaging said locking mechanism in the open position of said switch, and a casing carried by said switch blade for containing said locking mechanism, said casing having slots through its opposite walls for receiving an operating tool, said slots having one inclination to said switch blade at one end 120 and a different inclination to said switch blade at the other end of said slots, said locking mechanism comprising latching mechanism for engaging said catches, and two operating members articulating with 125 said latching mechanism, one of said oper- 130

- ating members overlapping said slots at one end thereof and the other of said operating members overlapping said slots at the other end thereof, whereby motion of either operating member away from the middle portion of said slots releases said latching mechanism, and a bracket carried by said switch blade between its pivot clip and its contact clip for supporting said casing.
- 10 7. In a locking switch of the lock-in lock-out type, the combination of a first support, a pivot clip carried by said support, a switch blade pivoted to said pivot clip, locking mechanism carried by said switch blade, a second support, a contact clip carried by said second support for engaging said switch blade in its closed position, a catch carried by said second support engaging said locking mechanism in the closed position of said switch, and a catch carried by said first support engaging said locking mechanism in the open position of said switch, and a casing carried by said switch blade for containing said locking mechanism, said casing having slots through its opposite walls for receiving an operating tool, said slots having one inclination to said switch blade at one end and a different inclination to said switch blade at the other end of said slots, said locking mechanism comprising latching mechanism for engaging said catches, and two operating members articulating with said latching mechanism, one of said operating members overlapping said slots at one end thereof and the other of said operating members overlapping said slots at the other end thereof, whereby motion of either operating member away from the middle position of said slots releases said latching mechanism,
- 15 30 35 40 45 50 55 60 65
- 40 a spring secured to said operating members and tending to hold them together, and an abutment carried by said casing for holding said operating members a sufficient distance apart to permit the insertion of an operating tool, and a bracket carried by said switch blade between its pivot clip and its contact clip for supporting said casing.
8. In a locking switch of the lock-in lock-out type, the combination of a first support, a pivot clip carried by said support, a switch blade pivoted to said pivot clip, locking mechanism carried by said switch blade, a second support, a contact clip carried by said second support for engaging said switch blade in its closed position, a catch carried by said second support engaging said locking mechanism in the closed position of said switch, and a catch carried by said first support engaging said locking mechanism in the open position of said switch, and a casing carried by said switch blade for containing said locking mechanism, said casing having slots through its opposite walls for receiving an operating tool, said slots having one inclination to said switch blade at one end and
- 70 75 80 85 90 95 100 105 110 115 120 125 130
- a different inclination to said switch blade at the other end of said slots, said locking mechanism comprising latching mechanism for engaging said catches and two pivoted operating members articulating with each other and with said latching mechanism, one of said operating members overlapping said slots at one end thereof and the other of said operating members overlapping said slots at the other end thereof, whereby motion of either operating member away from the middle portion of said slots releases said latching mechanism.
9. In a locking switch of the lock-in lock-out type, the combination of a first support, a pivot clip carried by said support, a switch blade pivoted to said pivot clip, locking mechanism carried by said switch blade, a second support, a contact clip carried by said second support for engaging said switch blade in its closed position, a catch carried by said second support engaging said locking mechanism in the closed position of said switch, and a catch carried by said first support engaging said locking mechanism in the open position of said switch, and a casing carried by said switch blade for containing said locking mechanism, said casing having slots through its opposite walls for receiving an operating tool, said slots having one inclination to said switch blade at one end and a different inclination to said switch blade at the other end of said slots, said locking mechanism comprising latching mechanism for engaging said catches and two pivoted operating members articulating with each other and with said latching mechanism, one of said operating members overlapping said slots at one end thereof and the other of said operating members overlapping said slots at the other end thereof, whereby motion of either operating member away from the middle portion of said slots releases said latching mechanism.
10. In a locking switch of the lock-in lock-out type, the combination of a first support, a pivot clip carried by said support, a switch blade pivoted to said pivot clip, locking mechanism carried by said switch blade, a second support, a contact clip carried by said second support for engaging said switch blade in its closed position, a catch carried by said second support engaging said locking mechanism in the closed position of said switch, and a catch carried by said first support engaging said locking mechanism in the open position of said switch, and a casing carried by said switch blade for containing said locking mechanism, said casing having slots through its opposite walls for receiving an operating tool.

an operating tool, said slots having one inclination to said switch blade at one end and a different inclination to said switch blade at the other end of said slots, said locking mechanism comprising latching mechanism for engaging said catches and two pivoted operating members articulating with each other and with said latching mechanism, one of said operating members overlapping said slots at one end thereof and the other of said operating members overlapping said slots at the other end thereof, whereby motion of either operating member away from the middle portion of said slots releases said latching mechanism, and a bracket carried by said switch blade between its pivot clip and its contact clip for supporting said casing.

11. In a locking switch of the lock-in lock-out type, the combination of a first support, a pivot clip carried by said support, a switch blade pivoted to said pivot clip, locking mechanism carried by said switch blade, a second support, a contact clip carried by said second support for engaging said switch blade in its closed position, a catch carried by said second support engaging said locking mechanism in the closed position of said switch, and a catch carried by said first support engaging said locking mechanism in the open position of said switch, and a casing carried by said switch blade for containing said locking mechanism, said casing having slots through its opposite walls for receiving an operating tool, said slots having one inclination to said switch blade at one end and a different inclination to said switch blade at the other end of said slots, said locking mechanism comprising latching mechanism for engaging said catches and two pivoted operating members articulating with each other and with said latching mechanism, one of said operating members overlapping said slots at one end thereof and the other of said operating members overlapping said slots at the other end thereof, whereby motion of either operating member away from the middle portion of said slots releases said latching mechanism, a spring secured to said operating members overlapping said slots at the other end thereof, whereby motion of either operating member away from the middle portion of said slots releases said latching mechanism, a spring secured to said operating members and tending to hold them together, and an abutment carried by said casing for holding said operating members a sufficient distance apart to permit the insertion of an operating tool, and a bracket carried by said switch blade between its pivot clip and its contact clip for supporting said casing.

12. In a locking switch of the lock-in lock-out type, the combination of a first support, a pivot clip carried by said support, a switch blade pivoted to said pivot clip, locking mechanism carried by said switch blade, a second support, a contact clip carried by said second support for engaging said switch blade in its closed position, a catch carried

by said second support engaging said locking mechanism in the closed position of said switch, and a catch carried by said first support engaging said locking mechanism in the open position of said switch, and a casing carried by said switch blade for containing said locking mechanism, said casing having slots through its opposite walls for receiving an operating tool, said slots having one inclination to said switch blade at one end and a different inclination to said switch blade at the other end of said slots, said locking mechanism comprising two pivoted latches, one for holding said switch in its closed position and the other for holding said switch in its open position, and two operating members articulating with said latches, one of said operating members overlapping said slots at one end thereof and the other of said operating members overlapping said slots at the other end thereof, whereby motion of either operating member away from the middle portion of said slots releases said latching mechanism.

13. In a locking switch of the lock-in lock-out type, the combination of a first support, a pivot clip carried by said support, a switch blade pivoted to said pivot clip, locking mechanism carried by said switch blade, a second support, a contact clip carried by said second support for engaging said switch blade in its closed position, a catch carried by said second support engaging said locking mechanism in the closed position of said switch, and a catch carried by said first support engaging said locking mechanism in the open position of said switch, and a casing carried by said switch blade for containing said locking mechanism, said casing having slots through its opposite walls for receiving an operating tool, said slots having one inclination to said switch blade at one end and a different inclination to said switch blade at the other end of said slots, said locking mechanism comprising two pivoted latches, one for holding said switch in its closed position and the other for holding said switch in its open position, and two operating members articulating with said latches, one of said operating members overlapping said slots at one end thereof and the other of said operating members overlapping said slots at the other end thereof, whereby motion of either operating member away from the middle portion of said slots releases said latching mechanism, a spring secured to said operating members and tending to hold them together, and an abutment carried by said casing for holding said operating members a sufficient distance apart to permit the insertion of an operating tool.

14. In a locking switch of the lock-in lock-out type, the combination of a first support, a pivot clip carried by said support, a switch blade pivoted to said pivot clip, a

locking mechanism carried by said switch blade, a second support, a contact clip carried by said second support for engaging said switch blade in its closed position, a 5 catch carried by said second support engaging said locking mechanism in the closed position of said switch, and a catch carried by said first support engaging said locking mechanism in the open position of said 10 switch, and a casing carried by said switch blade for containing said locking mechanism, said casing having slots through its opposite walls for receiving an operating tool, said slots having one inclination to said 15 switch blade at one end and a different inclination to said switch blade at the other end of said slots, said locking mechanism comprising two pivoted latches, one for holding said switch in its closed position and the 20 other for holding said switch in its open position and two pivoted operating members articulating with each other and with said latches, one of said operating members overlapping said slots at one end thereof and the 25 other of said operating members overlapping said slots at the other end thereof, whereby motion of either operating member away from the middle portion of said slots releases said latching mechanism. 30 15. In a locking switch of the lock-in lock-out type, the combination of a first support, a pivot clip carried by said support, a switch blade pivoted to said pivot clip, locking mechanism carried by said switch blade, a 35 second support, a contact clip carried by said second support for engaging said switch blade in its closed position, a catch carried by said second support engaging said locking mechanism in the closed position of said 40 switch, and a catch carried by said first support engaging said locking mechanism in the open position of said switch, and a casing carried by said switch blade for containing said locking mechanism, said casing having 45 slots through its opposite walls for receiving an operating tool, said slots having one inclination to said switch blade at one end and a different inclination to said switch blade at the other end of said slots, said locking mechanism comprising two pivoted latches, one for holding said switch in its closed position and the other for holding said switch in its open position, and two pivoted operating members articulating with 50 each other and with said latches, one of said operating members overlapping said slots at one end thereof and the other of said operating members overlapping said slots at the other end thereof, whereby motion of either 55 operating member away from the middle portion of said slots releases said latching mechanism, a spring secured to said operating members and tending to hold them together, and an abutment carried by said casing for holding said operating members a 60 65

sufficient distance apart to permit the insertion of an operating tool.

16. In a locking switch of the lock-in lock-out type, the combination of a first support, a pivot clip carried by said support, a switch 70 blade pivoted to said pivot clip, locking mechanism carried by said switch blade, a second support, a contact clip carried by said second support for engaging said switch blade in its closed position, a catch carried 75 by said second support engaging said locking mechanism in the closed position of said switch, and a catch carried by said first support engaging said locking mechanism in the open position of said switch, and a casing 80 carried by said switch blade for containing said locking mechanism, said casing having slots through its opposite walls for receiving an operating tool, said slots having one inclination to said switch blade at one end and 85 a different inclination to said switch blade at the other end of said slots, said locking mechanism comprising two pivoted latches, one for holding said switch in its closed position and the other for holding said switch 90 in its open position, and two operating members articulating with said latches, one of said operating members overlapping said slots at one end thereof and the other of said operating members overlapping said 95 slots at the other end thereof, whereby motion of either operating member away from the middle portion of said slots releases said latching mechanism, and a bracket carried by said switch blade between its pivot clip 100 and its contact clip for supporting said casing.

17. In a locking switch of the lock-in lock-out type, the combination of a first support, a pivot clip carried by said support, a switch 105 blade pivoted to said pivot clip, locking mechanism carried by said switch blade, a second support, a contact clip carried by said second support for engaging said switch blade in its closed position, a catch carried by 110 said second support engaging said locking mechanism in the closed position of said switch, and a catch carried by said first support engaging said locking mechanism in the open position of said switch, and a casing carried by said switch blade for containing said locking mechanism, said casing having slots through its opposite walls for receiving an operating tool, said slots having one inclination to said switch blade at one end and 115 a different inclination to said switch blade at the other end of said slots, said locking mechanism comprising two pivoted latches, one for holding said switch in its closed position and the other for holding said switch in its open position, and two operating members articulating with said latches, one of said operating members overlapping said slots at one end thereof and the other of said operating members overlapping said slots at the 120 other end thereof, whereby motion of either operating member away from the middle portion of said slots releases said latching mechanism, a spring secured to said operating members and tending to hold them together, and an abutment carried by said casing for holding said operating members a 125 130

other end thereof, whereby motion of either 5 operating member away from the middle portion of said slots releases said latching mechanism, a spring secured to said operating members and tending to hold them together, and an abutment carried by said casing for holding said operating members a sufficient distance apart to permit the insertion of an operating tool, and a bracket carried by said switch blade between its pivot clip and its contact clip for supporting said casing.

18. In a locking switch of the lock-in lock-out type, the combination of a first support, a pivot clip carried by said support, a switch blade pivoted to said pivot clip, locking mechanism carried by said switch blade, a second support, a contact clip carried by said second support for engaging said switch blade in its closed position, a catch carried by said second support engaging said locking mechanism in the closed position of said switch, and a catch carried by said first support engaging said locking mechanism in the open position of said switch, and a casing carried by said switch blade for containing said locking mechanism, said casing having slots through its opposite walls for receiving an operating tool, said slots having one inclination to said switch blade at one end and a different inclination to said switch blade at the other end of said slots, said locking mechanism comprising two pivoted latches, one for holding said switch in its closed position and the other for holding said switch in its open position, and two pivoted operating members articulating with each other and with said latches, one of said operating members overlapping said slots at one end thereof and the other of said operating members overlapping said slots at the other end thereof, whereby motion of either operating member away from the middle portion of said slots releases said latching mechanism, and a bracket carried by said switch blade between its pivot clip and its contact clip for supporting said casing.

19. In a locking switch of the lock-in lock-out type, the combination of a first support, a pivot clip carried by said support, a switch blade pivoted to said pivot clip, locking mechanism carried by said switch blade, a second support, a contact clip carried by said second support for engaging said switch blade in its closed position, a catch carried by said second support engaging said locking mechanism in the closed position of said switch, and a catch carried by said first support engaging said locking mechanism in the open position of said switch, and a casing carried by said switch blade for containing said locking mechanism, said casing having slots through its opposite walls for receiving an operating tool, said slots hav-

ing one inclination to said switch blade at one end and a different inclination to said switch blade at the other end of said slots, said locking mechanism comprising two pivoted latches, one for holding said switch 70 in its closed position and the other for holding said switch in its open position, and two operating members articulating with each other and with said latches, one of said operating members overlapping said 75 slots at one end thereof and the other of said operating members overlapping said slots at the other end thereof, whereby motion of either operating member away from the middle portion of said slots releases said 80 latching mechanism, a spring secured to said operating members and tending to hold them together, and an abutment carried by said casing for holding said operating members a sufficient distance apart to permit the 85 insertion of an operating tool, and a bracket carried by said switch blade between its pivot clip and its contact clip for supporting said casing.

20. In a locking switch of the lock-in lock-out type, the combination of a first support, a pivot clip carried by said support, a switch blade pivoted to said pivot clip, locking mechanism carried by said switch blade, a second support, a contact clip carried by said second support for engaging said switch blade in its closed position, a catch carried by said second support engaging said locking mechanism in the closed position of said switch, and a catch carried by said first support engaging said locking mechanism in the open position of said switch, and a casing carried by said switch blade for containing said locking mechanism, said casing having slots through its opposite walls for 105 receiving an operating tool.

21. In a locking switch of the lock-in lock-out type, the combination of a first support, a pivot clip carried by said support, a switch blade pivoted to said pivot clip, locking mechanism carried by said switch blade, a second support, a contact clip carried by said second support for engaging said switch blade in its closed position, a catch carried by said second support engaging said locking mechanism in the closed position of said switch, and a catch carried by said first support engaging said locking mechanism in the open position of said switch, and a casing carried by said switch blade for containing 110 said locking mechanism, said casing having slots through its opposite walls for receiving an operating tool, and a bracket carried by said switch blade between its pivot clip and its contact clip for supporting said 120 casing.

In witness whereof, I hereunto subscribe my name this 25th day of October, A. D. 1917.

EDSON O. SESSIONS.
